UNITED STATES PATENT OFFICE

KURT WANDEL, OF NEW YORK, N. Y., ASSIGNOR TO NATIONAL CELLULOSE CORPORATION, A CORPORATION OF NEW YORK

TISSUE PAD

Application filed January 9, 1929, Serial No. 331,339. Renewed April 16, 1931.

The object of my invention is to provide a pad of facial tissue of novel form, whereby the pad may be carried in a vanity case in the same manner as a powder puff, requiring little if any more room, although providing a substantial supply of facial tissue.

My invention also provides a novel method of making such pads whereby the cost of the tissue in pad form is but little more than in sheet form in which it is now supplied.

My invention is illustrated in the accompanying drawings wherein

Fig. 1 is a perspective view showing the manner of using the pad;

Fig. 2 is perspective view of a typical pad;

Fig. 3 is a cross section through the corner thereof;

Fig. 4 is a plan view of the pad showing how the sheet of tissue after being used, is removed from the pad;

Fig. 5 is a plan view of one of the dies used for cutting the pads; and

Fig. 6 is a cross-section through the cutting dies on the line 6—6 of Fig. 5.

The pad is composed of about seventy-five sheets of the so-called facial tissue. The pads may be of various sizes, Fig. 2 of the drawing showing in full scale a pad of average size.

The sheets of the pad are preferably shaped as shown, that is, square or rectangular with one rounded corner, as indicated at 1, with the sheets adhering together along the edges 2 and 3 which meet at the rounded corner. Near the rounded corner the sheets are pressed together as shown at 4, for the double purpose of causing the sheets to better adhere and also to give a certain amount of stiffness to the pad at this corner whereby it may conveniently be gripped when using the pad.

The two rounded edges of the pad and the "eye" or pressed portion are formed at one operation of a stamping press. No adhesive or moisture is required. The soft sheets under the pressure of the die are caused to adhere together to such an extent that the

pad will remain intact under ordinary conditions of usage until completely used up. The single sheets are readily separated from the pads in the manner shown in Fig. 3 without any tendency to tear, notwithstanding the fact that facial tissue sheets are very soft and of little tensile strength, even as compared with ordinary tissue paper. This is due to the fact that no adhesive is used between the sheets, the sheets being held together by the interlocking fibres of the sheets themselves which readily come apart when the sheet is lifted off the pad as indicated.

In making up the pads a block of the desired number of sheets, say seventy-five, four times the size of the finished pad, is subjected to a single operation of a cutting die of the shape indicated in Fig. 5, thereby simultaneously forming the rounded corners, adhering edges and eyelets of four pads at each operation.

As shown, the upper and lower dies are each provided with cutting knives 6 projecting from the face of the dies. The knives are exactly opposed so that the edges come together upon the operation of the press, thereby pressing the sheets together before actually cutting through them.

Each of these dies is also provided with four raised portions 7 for pressing the sheets together near the rounded corners. In the pad illustrated in the drawings these pressed-together portions are in the form of a washer or eyelet, the center of the circle being punched out by a punching die 8. The pressed-together portion, however, may be of any desired shape, and the die may be provided with raised letters for embossing the trade-mark of the manufacturer or other appropriate insignia upon the pads at each operation of the die. One of the dies is also preferably provided with an ejector 9 for punching out the center of the block of sheets which is cut out by the dies in producing the rounded corners of the pads.

The sheets are not detached from the pad before using, as an ordinary sheet of tissue is employed, for the reason that the sheets are of such small size that a single sheet when folded or bunched together enough to

grasp, does not afford adequate surface. Instead, the entire pad is used in the manner indicated in Fig. 1, by taking hold of it at the rounded corner where the eyelet is located. This stiffer portion afforded by the eyelet may be easily gripped in such manner that substantially the whole surface of the sheet is available. Also the thickness of the pad makes it easier to use by sup-

10 plying a backing to the sheet having an exposed surface.

After using, as indicated, the outer or soiled sheet is removed from the pad and thrown away, leaving a fresh sheet exposed

15 ready for use.

I claim:

1. A pad of facial tissue comprising a plurality of sheets having their edges held together along one edge solely by the interlocking fibres of the sheets.

2. A pad of facial tissue consisting of a plurality of sheets, the said sheets being pressed together in adhering relation through a portion of limited area.

25 3. A pad of facial tissue consisting of a plurality of sheets, the said sheets being pressed together in adhering relation through a portion of limited area near one corner of the sheets.

30 4. A pad of facial tissue comprising a plurality of sheets having their edges held together along one edge solely by the interlocking fibres of the sheets, the said sheets being pressed together in adhering relation through a portion of limited area.

35 5. A pad of facial tissue comprising a plurality of sheets having their edges held together along two meeting edges solely by the interlocking fibres of the sheets.

6. A pad of facial tissue comprising a plurality of sheets having their edges held together along two meeting edges solely by the interlocking fibres of the sheets, the said sheets being pressed together in adhering relation through a portion of limited area near the meeting edges.

7. The method of producing facial tissue pads which comprises stamping such pads out of a block of sheets by means of knives which compress the edges of the sheets into adhering contact as the pads are cut.

8. The method of producing facial tissue pads which comprises stamping such pads out of a block of sheets by means of knives which compress the edges of the sheets into adhering contact as the pads are cut, and simultaneously pressing the sheets together at a point of limited area to form a stiffened portion and cause the sheets to adhere together.

9. The method of producing facial tissue pads which comprises simultaneously stamping a plurality of pads out of a block of

sheets by means of knives which compress the edges of the sheets into adhering contact as the pads are cut.

In testimony whereof I affix my signature.

KURT WANDEL.
